BOW TIE BRACKET

Louis Strauss, Bronx, N. Y.

Application January 2, 1953, Serial No. 22,978

Term of patent 3½ years

(Cl. D17—10)

Fig. 1.

Fig. 2.

Fig. 3.

Fig. 1 is a front view of a bow tie bracket showing my new design;

Fig. 2 is a side elevation thereof; and

Fig. 3 is a top plan view thereof.

I claim:

The ornamental design for a bow tie bracket, as shown.
